UNITED STATES PATENT OFFICE.

OTTO BUCHHORN, OF CHARLOTTENBURG, GERMANY, ASSIGNOR TO INHABAD-
GESELLSCHAFT M. B. H., OF CHARLOTTENBURG, NEAR BERLIN, GERMANY.

APPARATUS FOR CREATING ARTIFICIAL BREATHING.

1,245,867.

Specification of Letters Patent.

Patented Nov. 6, 1917.

Application filed July 16, 1914. Serial No. 851,383.

To all whom it may concern:

Be it known that I, OTTO BUCHHORN, a subject of the German Emperor, residing at Charlottenburg, near Berlin, Germany, 5 have invented certain new and useful Improvements in Apparatus for Creating Artificial Breathing; and I do hereby declare the following to be a full, clear, and exact description of the invention, such as will 10 enable others skilled in the art to which it appertains to make and use the same.

My invention relates to an apparatus for creating artificial breathing, in which a rhythmical expansion and contraction of 15 the chest is brought about by moving the arms of the person, with which a direct compression of the chest by means of a compressing device can be combined, said compressing device being connected to the devices which move the arms of the person 20 by means of suitable connecting members. An apparatus suitable for this purpose is shown in Patent No. 1,057,633 of Fries.

The object of my invention is to effect an 25 introduction of oxygen during the inhaling period in addition to the mechanical artificial breathing in certain cases of apparent death.

A source of oxygen, for example, a vessel 30 containing liquid oxygen is connected to the apparatus, a tube being led from said source of oxygen to a breathing device which is to be placed on the person, such as a mask or a tube or mouth-piece to be introduced into the mouth.

At the same time means are provided for connecting the supply of oxygen to the breathing device during the inhaling period, and to disconnect said supply during 40 the exhaling period. For this purpose a positively controlled valve or any other suitable device can be utilized.

Two forms of construction of the invention are shown by way of example in the 45 drawings.

Figure 1 shows one form of construction in side elevation and partly in section,

Fig. 2 shows a view from below,

Fig. 2^a shows a section through a detail, 50 Figs. 3 and 4 show the controlling valve for the oxygen supply in two different positions,

Fig. 3^a shows a further detail,

Fig. 5 shows the second form of construction as seen from below,

Fig. 6 shows the second form of construction in side elevation.

The apparatus shown in Figs. 1-4 is provided with a stretcher 1 on which is laid the person requiring treatment, said 60 stretcher being provided with a downwardly sloping support 2 for the head of the person. The lower end of the stretcher 1 rests on two feet 3. Near the head end of the stretcher a plate 4 is attached on the 65 lower surface, with which two tubes 5 are rigidly connected. These tubes are provided near their outer ends with feet 6, which thus serve for supporting the head end of the stretcher 1. Through the tubes 5 a 70 shaft 7 extends, to the ends of which two levers 8 are attached. To the free ends of these levers a cross-bar 9 is fixed, which serves simultaneously as a reinforcing member and as a handle for the person operating 75 the apparatus.

Manacles 10 with straps 11 for attaching the arms of the person requiring treatment are movably mounted on the levers 8, so that an adjustment of same according to the 80 length of the arms is possible. The levers 8 are extended beyond the shaft 7 as shown at 8^a and are provided at these ends with eyes 12 in which cords 13 are fastened. The stretcher 1 is made narrow at the head end 85 and widens out toward the lower end. Rods 15 are fixed in holders 14 parallel to the slanting sides of the stretcher, said rods being provided with a number of holes 16. Each rod 15 is provided with a movable 90 slide 17 which has an opening 18, so that the slide can be fixed in any desired position by means of a pin 65 passing through said opening 18 and one of the holes 16 of the rod 15 according to the size of the person to be treated. Each of the slides 17 is 95 provided with a pulley 19 over which the cord 13 is passed. The two cords engage by means of hooks 20 arranged at their ends in holes 22 of a compressor 21 serving to 100 contract the chest. This compressor is provided with several eyes 22 to allow of adjustment according to the size of the person.

As far as now described, the apparatus corresponds in its action to that of Patent 105 1057633. It is evident that when the system of levers 8 is in the position shown in Fig. 2 (compare the position *a* shown dotted in Fig. 1), the cords 13 exert a tension on the compressor 21, so that the chest of the per- 110

- son undergoing treatment is contracted. If on the other hand, the system of levers 8 is swung back into the position shown in Fig. 1, and still further into the position shown at *b*, then the cords 13 become slack and the pressure of the compressor on the chest is removed, so that the chest can expand freely to correspond with the movement of the arms.
- 10 Below the stretcher there is further provided a vessel 24 supported in holders 23, said vessel containing liquid or compressed oxygen. From the valve 25 of the vessel a tube 26 extends to the pressure reducing valve 27, with which a pressure-gage 28 is connected. From the reducing valve 27 a tube 29 leads to the bag-like accumulator 30, which lies between the stretcher 1 and a plate 51 which is guided along rods 52 which are attached vertically to the stretcher. Spiral springs 53 surround the rods 52, said springs bearing at one end against the plate 51 and at the other end against the heads 54 of the rods 52 and tending to press the bag 30 together by means of the plate 51. The bag is provided with a safety valve 31 from which a tube 32 leads to a controlling valve 33. The plug 34 of the latter is provided with an axial bore 61 and a slot 62 communicating with said bore. A passage 63 in the valve casing corresponds to said slot, the pipe 32 being connected to the passage 63. The bore 61 of the valve leads into an axial standard 64 of the valve casing to which is connected a tube 49 having a breathing mask or respirator 50 attached to the end. A lever 35 is attached to the plug 34 of the valve 33 and a torsional spring 36 is arranged in connection therewith which has the tendency to keep the valve always in the closed position (Fig. 3).
- 45 A lever 38 is mounted at 39 on a bearing 37. Into the box-shaped head 40 (Fig. 2^a) of this lever is led a pin 41 which is subjected to the action of a spring 42 acting in its longitudinal direction. Further a fixed pivot 43 is arranged on the other side of the head 40, with which a rod 44 engages, the other end of said rod being jointedly connected to an arm 45 fixed to the shaft 7. The pivot 39 of the lever 38 is so disposed in relation to the pivot of the arm 35 that, when the lever moves from the position shown dotted in Fig. 3 to the position shown in Fig. 4, the pin 41 first engages the arm 35 and rotates the same around to the position shown in Fig. 4, the pin 41 gradually approaching the end of the arm during such movement. A slight further movement of 60 lever 38, as will be understood from Fig. 4, releases the arm 35 and permits it to fly back under the action of the spring 36.
- 65 The action of the apparatus described above is as follows:—
- When it is desired to use the apparatus,

the valve 25 of the vessel 24 is opened and remains open during the entire period of use. Consequently oxygen flows continuously from the vessel through the reducing valve 27 and the tube 29 into the bag 30, 70 from which it passes into the valve 33 by way of the casing of the safety valve 31 and the tube 32. If the system of levers 8 is in the position *a*, then the valve 33 is closed, so that the way to the tube 49 is closed to 75 the oxygen. Consequently the whole of the oxygen issuing from the vessel is collected by the bag 30 which is correspondingly inflated.

If now the system of levers 8 is moved in 80 the direction of the arrow (Fig. 1), whereby the arms of the person are raised, then the pin 41 of the lever 38 which is moved by the action of the rods 45, 44 engages with the arm 35 and thus rotates the plug 34 in 85 such a manner that the slot 62 enters into communication with the passage 63 in the valve casing, so that oxygen can flow from the pipe 32 into the bore 61 of the plug and thence through the tube 49 to the breathing 90 mask 50. Just before the system of levers 8 has arrived into the stretching position *b* (Fig. 1) then the end edge of the arm 35 has reached the position shown in Fig. 4, so that on completing the movement of the 95 levers 8 the arm 35 slides away from the pin 41 and the valve-plug 34 returns to the closed position (Fig. 3), in which it is retained by means of a stop 46.

The supply of oxygen from the vessel 24 100 to the bag 30 is regulated in such a manner that the amount of oxygen stored in the bag during the exhaling period together with the oxygen flowing in also during the inhaling period corresponds to the quantity 105 which must be supplied to the patient during one inhaling period. The bag 30 will thus be emptied by the pressing action of the spring-loaded plate 51 during the inhaling period. 110

During the exhaling period when the system of levers 8 moves from the position *b* (Fig. 1) back again into the position *a*, the pin 41 engages with the inclined back of the arm 35 (Figs. 3 and 3^a) by the action 115 of which it is pushed back into the head 40 in opposition to the spring 42. As soon as the pin has passed the arm 35, it again snaps forward, so that the entire apparatus again comes into its original position, and 120 a new inhaling can be started.

In the form of construction shown in Figs. 5 and 6, the feet 6 arranged at the head end are formed as holders for the oxygen vessel 24. From the pressure-reducing valve 27 125 attached to the oxygen vessel, a short tube 55 leads to one of the limbs of a T-piece 56. To the other two limbs of the T-piece are connected on the one hand the bag 30 and on the other hand the tube 49 leading to the 130

breathing mask. In the limb to which is connected the tube 49 there is provided a valve 57 which rests on its seat under a slight spring action and which opens in the direction toward the tube 49 under a certain pressure of oxygen.

The bag lies between the stretcher 1 and a broad leather belt 58 which is attached at one end at 59 to the stretcher 1 and at the other end to a roller or drum 60 mounted on the shaft 7.

The action of this apparatus is as follows:—

If the system of levers 8 is in the position shown, then the belt 58 hangs slack, so that the bag 30 can be inflated and can receive the oxygen emerging from the vessel 24. The pressure with which the oxygen fills the bag is not sufficient to open the valve 57. If now 20 the system of rods is moved in the direction of the arrow, which corresponds to the inhaling period, then the end of the belt 58 is wound around the drum 60. The belt 58 is thereby tensioned and presses the bag 30 together. Under this pressure the valve 57 opens, so that the oxygen flows to the respirator through the tube 49 from the bag 30 together with the oxygen flowing constantly from the bottle 24 through the 30 tube 55.

The valve 57 serves simultaneously as safety valve, since, if the movement of the arms is stopped, it opens as soon as the bag 30 has become quite filled with oxygen.

In Figs. 5 and 6 a device is also shown, which renders it possible to exert a strong longitudinal pull on the body of the patient together with the swinging movement of the arms. For this purpose a device is arranged 40 at the foot-end of the stretcher, to which the feet of the patient may be strapped. In order not to make the apparatus too long and unwieldy hereby, the foot-strapping device is arranged movably and preferably slidably.

For this purpose a guiding tube 70 is arranged underneath the stretcher 1, in which a rod 71 is slidable. At the end of the rod 71 a rest 72 for the feet is arranged, which latter can be held by means of a strap 73. According to the size of the patient the rod 71 is drawn more or less out of the tube 70 and fixed by means of a screw 74.

The stretching device is primarily intended for use in cases in which the chest compressor must be placed entirely out of action or else adjusted so as to be brought only slightly into action, as must be done for example in cases of drowning, in which the effecting of energetic pressure must be avoided on account of the danger attached thereto owing to the flooding of the internal organs. This novel feature can therefore preferably be used in apparatus which has no device at all for compressing the chest.

Although apparatus with devices for con-

tracting the chest corresponding to the movements of the arm levers are described and illustrated herein, my invention is not restricted to such apparatus. It refers also to apparatus in which only means for moving the arms are provided. It is to be observed, namely, that in certain cases of accident, the use of pressure on the body is not desirable. In such cases, apparatus without compression devices for the chest can be used, or in the case of apparatus which are fitted with such a device, the latter can be placed out of action.

Having now described my invention what I claim as new and desire to secure by Letters Patent is:—

1. An apparatus for creating artificial breathing, comprising means for moving the arms of the patient, a source of oxygen, and means controlled by the arm moving means 85 for supplying oxygen from said source to the breathing organs of the patient.

2. An apparatus for creating artificial breathing, comprising means for moving the arms of the patient, a source of oxygen, 90 means for supplying oxygen from said source to the breathing organs of the patient and means for establishing connection between the source of oxygen and the breathing organs during the movement of the arm moving device corresponding to the inhaling period and for interrupting said connection during the movement corresponding to the exhaling period.

3. An apparatus for creating artificial 100 breathing, comprising means for moving the arms of the patient, a source of oxygen, a duct for leading oxygen from said source to the breathing organs of the patient, and a valve controlling said duct.

4. An apparatus for creating artificial breathing, comprising means for moving the arms of the patient, a source of oxygen, a duct for leading oxygen from said source to the breathing organs of the patient, a valve 110 contained in said duct, and an accumulator connected to said duct, and means for pressing the stored-up oxygen from the accumulator, during the inhaling movement.

5. An apparatus for creating artificial 115 breathing, comprising means for moving the arms of the patient, a source of oxygen, a duct for leading oxygen from said source to the breathing organs of the patient, a valve contained in said duct, an accumulator connected to said duct, said accumulator being in the form of a bag, and means for compressing said bag during the inhaling period.

6. An apparatus for creating artificial 125 breathing, comprising means for moving the arms of the patient, a source of oxygen, a duct for leading oxygen from said source to the breathing organs of the patient, a bag connected to the duct for receiving oxygen 130

during the exhaling movement, a compressing belt for the bag, means for tensioning said belt during the inhaling movement, and a spring-controlled valve contained in the 5 duct leading from the bag to the breathing organs, the spring of said valve being overcome by the pressure which results when the bag is compressed.

7. An apparatus for creating artificial breathing, comprising means for moving the 10 arms of the patient, a source of oxygen, a duct for leading oxygen from said source to the breathing organs of the patient, a bag connected to the duct for receiving 15 oxygen during the exhaling movement, a drum mounted on a shaft of the arm-moving device, a compressing belt for the bag, said belt being fixed to said drum in such a manner, that during the inhaling movement it 20 is partly wound on to the drum and thus tensioned, and a spring-controlled valve contained in the duct leading from the bag to the breathing organs, the spring of said valve being overcome by the pressure which 25 results when the bag is compressed.

8. An apparatus for creating artificial breathing, comprising means for moving the arms of the patient, a device for contracting the chest connected to the arm-moving 30 means, a source of oxygen, means for supplying oxygen from said source to the breathing organs of the patient and means for establishing connection between the source of oxygen and the breathing organs 35 during the movement of the arm-moving device corresponding to the inhaling period and for interrupting said connection during the movement corresponding to the exhaling period.

40 9. An apparatus for creating artificial breathing, comprising means for moving the arms of the patient, a device for contracting the chest connected to the arm-moving means, a source of oxygen, a duct for leading 45 oxygen from said source to the breathing organs of the patient, a valve in said duct, an accumulator connected to said duct, and means for pressing the stored-up oxygen from the accumulator during the inhaling movement.

50 10. An apparatus for creating artificial breathing, comprising means for moving the arms of the patient, a device for contracting the chest connected to the arm-moving 55 means, a source of oxygen, a duct for lead-

ing oxygen from said source to the breathing organs of the patient, a bag connected to the duct for receiving oxygen during the exhaling movement, and means for compressing said bag during the inhaling 60 period.

11. An apparatus for creating artificial breathing, comprising means for moving the arms of the patient and means for securing the feet of the patient. 65

12. An apparatus for creating artificial breathing, comprising means for moving the arms of the patient, means for securing the feet of the patient, said feet-securing means being adjustable according to the size of the 70 patient.

13. An apparatus for creating artificial breathing, comprising means for moving the arms of the patient, means for securing the feet of the patient, said feet-securing means 75 being adjustable according to the size of the patient, and being arranged on a rod which is adjustable in the longitudinal direction of the apparatus and which is fixable in the desired position. 80

14. An apparatus for creating artificial breathing, comprising means for moving the arms of the patient, a source of oxygen, means for supplying oxygen from said source to the breathing organs of the patient 85 and means for securing the feet of the patient, said feet-securing means being adjustable according to the size of the patient.

15. An apparatus for creating artificial breathing, comprising means for moving the arms of the patient, a device for contracting the chest connected to the arm-moving means, a source of oxygen, means for supplying oxygen from said source to the breathing organs of the patient, means for establishing connection between the source of oxygen and the breathing organs during the movement of the arm-moving device corresponding to the inhaling period and for interrupting said connection during the 100 movement corresponding to the exhaling period, and means for securing the feet of the patient.

In testimony whereof, I affix my signature, in presence of two witnesses.

OTTO BUCHHORN.
